(57) **CLAIM**

We claim the ornamental design for an intraoral x-ray sensor, as shown and described.

DESCRIPTION

FIG. 1 is a back perspective view of an intraoral x-ray sensor showing our new design;

FIG. 2 is a top view thereof;

FIG. 3 is a bottom view thereof;

FIG. 4 is a left view thereof;

FIG. 5 is a right view thereof;

FIG. 6 is a front view thereof; and,

FIG. 7 is a back view thereof.

The broken-line showing of the environment is for illustrative purposes only and forms no part of the claimed design. The broken lines which define the boundaries of the claimed design form no part thereof.
